FIRING MECHANISM

Leslie A. Skinner, Berkeley, Calif., and Julius A. Foise, Miami, Fla., assignors to the United States of America as represented by the Secretary of War

Application January 31, 1944, Serial No. 520,418

3 Claims. (Cl. 42—69)

(Granted under the act of March 3, 1883, as amended April 30, 1928; 370 O. G. 757)

1

The invention described herein may be manufactured and used by or for the Government for governmental purposes, without the payment to us of any royalty thereon.

This invention relates to a firing mechanism, more particularly to a semi-automatic firing mechanism for a rocket launcher.

It is an object of this invention to provide a firing mechanism for a rocket launcher that is cocked by the action of the gas blast of the rocket projectile or manually.

The specific nature of the invention as well as other objects and advantages thereof will clearly appear from a description of a preferred embodiment as shown in the accompanying drawing in which:

Fig. 1 is a fragmentary longitudinal sectional view of a rocket projector showing the arrangement of the firing mechanism.

Fig. 2 is an enlarged detail view of the sear and trigger arrangement.

The firing mechanism embodying this invention is shown in assembled relation on a rocket projector. A trigger housing 25 and hammer housing 30 are suitably secured to the underside of rocket projector tube 35 as by welding. A cocking lever 10 is pivotally mounted on the forward portion of trigger housing 25 by a transverse pin 2. The cocking lever 10 is preferably integrally formed with a pistol grip 56 as shown in the drawing and a spring catch 3 is provided to secure such grip to housing 25. Catch 3 comprises a spring portion 5 and an integral head portion 6. The lower corner of head portion 5 engages a notch 7 provided in trigger housing 25. Catch 3 is secured to pistol grip 56 as by a screw 4. The upper end of catch 3 is of such shape that it may be conveniently engaged by the thumb of the operator in order to disengage such catch from notch 7 so that pistol grip 56 and lever 10 may be pivoted downwardly as shown in dotted outline in the drawing for a purpose to be described.

A hammer 20 is pivotally mounted within hammer housing 30 as by a pin 14. Hammer 20 is provided with an integral lug 15 near the pivoted end of hammer 20. A transverse hole 16 is provided in lug 15 which is spaced from the pivotal axis of hammer 20. A firing pin 17 is integrally formed on the upper end of hammer 20 as shown in the drawing. Firing pin 17 is arranged to strike a conventional primer 18 such as utilized in small arms cartridges which is axially mounted at the rear end of a rocket 19 placed within launcher tube 35.

2

A rod 21 is provided to connect hammer 20 with a hammer spring 22. Hammer spring 22 is horizontally mounted within a hammer spring housing 8 mounted on the underside of launcher tube 35 within trigger housing 25 and suitably secured to tube 35 as by welding. Hammer spring housing 8 comprises a hollow thin walled member which defines a cylindrical recess 13. Hammer spring 22 surrounds rod 21 and the right end of rod 21 as shown in the drawing is upset over a washer 23 to secure rod 21 to spring 22. The other end of rod 21 is pivotally connected to hammer 20 by inserting a bent end portion of rod 21 thru hole 16 in lug 15. A push rod 11 is pivotally secured to the upper end of cocking lever 10 by a pin 12 and projects into hammer spring housing 8 thru an elongated hole 9.

A sear 24 is pivotally mounted within housing 25 by a transverse pin 26 directly underneath hammer spring housing 8 as shown in the drawing. Sear 24 comprises an integral upstanding lug 27 which has a downwardly sloped top surface 28. Lug 27 projects upwardly thru a hole 29 in the bottom of spring housing 8 where it engages the right hand surface of washer 23. An integral arm 31 projects forwardly in a horizontal plane from lug 27 as shown in the drawing. A spring 32 is placed between arm 31 on the top end thereof and the underside of spring housing 8 to bias arm 31 downwardly and hence pivot lug 27 into the path of washer 23. An integral rearwardly projecting lug 33 is provided on the rear of sear 24 having a horizontal flat top surface 34 which is engaged by a disconnector 36 to be presently described.

A trigger 1 is pivotally mounted within housing 25 by a transverse pin 37. Trigger 1 is of conventional configuration and is arranged to be biased against the pressure of the operator's finger by a spring 38 horizontally mounted in back of the center of trigger 1. One end of spring 38 rests within a recess 39 in the back of trigger 1 while the other end of spring 38 abuts a transverse pin 40 mounted in trigger housing 25. The disconnector 36 comprises a bifurcated member which straddles trigger 1 and is pivotally mounted on the upper end thereof by a transverse pin 41. A forwardly projecting end 53 of disconnector 36 engages the flat surface 34 of lug 33. A sloped surface 42 is provided on the end of disconnector 36 to ride on a sloped surface 57 provided on the underside of lug 33. A spring 43 surrounds pin 41 and is connected in such fashion so as to bias disconnector 36 in a counterclockwise direction as shown in the drawing. A pin 44 radially dis-

posed to pin 41 and suitably secured thereto is provided to limit the counterclockwise movement of disconnector 36 when such pin strikes a transverse pin mounted on trigger 1. A transverse pin 46 mounted in back of sear 24 limits the clockwise rotation of sear 24 to the position shown in the drawing.

A rocket positioning detent 47 is provided on the periphery of projector tube 35 to retain the rocket projectile in its proper location within tube 35. Detent 47 comprises a lever 48 and a conically shaped plunger 49. Lever 48 is pivotally mounted within a bracket 50 by a transverse pin 51. Bracket 50 is secured to the top of tube 35 as by welding. A spring 53 rests in a recess 52 provided on the underside of lever 48 and on top of tube 35 to bias the plunger 49 downwardly thru a hole 54 in tube 35 to engage an annular groove 55 provided about the outer periphery of rocket 19.

In the uncocked position of the mechanism hammer 20 is vertical and washer 23 is held adjacent the end of hammer spring housing 8 by hammer spring 22. Hammer 20 is cocked by unlatching catch 3 out of engagement with notch 7 in housing 25 by pressing outwardly and downwardly on the head 6 of catch 3. This frees pistol grip 56 so that such grip and lever 10 may be pivoted about pin 2 to the position shown in dotted outline in Fig. 1. This movement forces push rod 11 against the upset end of connecting rod 21 and moves connecting rod 21 to the left as shown in the appended drawing. This movement forces washer 23 to ride over the sloped surface 28 of sear 24 thereby rotating the sear in a counterclockwise direction out of the path of washer 23. As rod 21 is forced to the left the hammer 20 is lowered to a horizontal position within hammer housing 30. When washer 23 clears the end of lug 27 spring 32 immediately pivots sear 24 into engagement with the rear surface of washer 23. Lever 10 is then returned to the closed position whereupon catch 3 engages notch 7 thereby locking lever 10 in the closed position and removing push rod 11 from the end of connecting rod 21. The bias of hammer spring 22 forces lug 27 against pin 45 thereby preventing rotational movement in a clockwise direction of sear 24 about pin 26 and hence retains washer 23 and hammer 20 in the cocked position shown in Fig. 1.

The rocket projectile 19 is inserted in the rear of tube 35 and is positioned therein by detent 47 which is biased into groove 55 in rocket 19 by spring 53. Rocket 19 is discharged when trigger 1 is pulled to the left as shown in the drawing. When the trigger is pulled the disconnector 36 bears against the flat surfaces 34 of lug 33 of sear 24 and forces sear 24 to rotate in a counterclockwise direction about pin 26. When the uppermost end of lug 27 clears the end of washer 23, spring 22 immediately forces washer 23 and hence rod 21 to the right. This movement is transmitted to the hammer 20 thru the connection of rod 21 to hammer 20 thereby pivoting hammer 20 to an upright position, whereupon firing pin 17 strikes primer 18 a smart blow thereby effecting discharge of rocket projectile 19. As trigger 1 is pulled rearwardly to its fullest extent disconnector 36 continues to rotate sear 24 in a counterclockwise direction until disconnector 36 slips off of the flat surface 34 of lug 33. Immediately disconnector 36 be-

comes disengaged from surface 34, spring 32 biases the lug 27 in a clockwise direction upwardly thru hole 29 into the path of washer 23.

The gas blast resulting from the discharge of rocket 19 strikes against the raised hammer 20 and pivots it rearwardly to the cocked position. In so doing, connecting rod 21 is forced to the left as viewed in the drawing, thereby causing washer 23 to ride along the sloped surface 28 of sear 24 camming such sear out of its path and placing spring 22 under compression. As washer 23 passes over the sloped surface 28 of sear 24, spring 32 immediately biases lug 27 into the path of washer 23 thereby holding the hammer 20 in a cocked position. It should be noted however that the maintenance of trigger pull on trigger 1 keeps disconnector 36 pivoted out of the path of sear extension 33. Trigger 1 must be released before the mechanism is placed in condition to again release sear 24. When the trigger 1 is released, spring 38 biases such trigger forwardly and spring 43 of disconnector 36 permits the sloped surface 42 of disconnector 36 to slide past the sloped underside 57 of lug 33 whereupon the disconnector will engage the flat surface 34 of sear 24. The mechanism is then in the cocked position and is ready to fire.

From the foregoing description it is readily apparent that a positive semi-automatic firing mechanism for a rocket projector is hereby provided which can be cocked either manually or by the gas blast of the rocket projectile.

We claim:

1. In a firearm of the type having a trigger housing and a hammer pivotally movable into and out of the bore of the firearm and controlled by a spring-pressed operating rod terminating forwardly in the trigger housing, the improvement comprising a trigger guard pivotally mounted on said trigger housing as a first-class lever, and having on its distal end a plunger arranged to engage and move said operating rod to the cocked position on pivotal movement of said trigger guard.
2. In a firearm of the type having a trigger housing and a hammer pivotally movable into and out of the bore of the firearm and controlled by a spring-pressed operating rod terminating forwardly in said trigger housing, the improvement comprising a trigger guard pivotally mounted on said trigger housing as a first-class lever, and having on its distal end a plunger extending into said trigger housing for actuating the operating rod.
3. In a device as in claim 2, a slip-spring catch for said trigger guard in its normal position.

LESLIE A. SKINNER.
